UNITED STATES PATENT OFFICE.

WILLIAM H. BURNHAM AND JOHN H. MILLER, OF BATAVIA, ILLINOIS, AS-SIGNORS TO THE UNITED STATES WIND ENGINE AND PUMP COMPANY, OF SAME PLACE.

HAY-CARRIER-TRACK HANGER.

SPECIFICATION forming part of Letters Patent No. 387,142, dated July 31, 1888.

Application filed March 26, 1888. Serial No. 268,459. (No model.)

To all whom it may concern:

Be it known that we, WILLIAM H. BURNHAM and JOHN H. MILLER, citizens of the United States, and residents of Batavia, in the county of Kane and State of Illinois, have invented new and useful Improvements in Hangers for Tracks of Hay Carriers, of which the following is a specification, reference being had to the accompanying drawings, illustrating the invention, in which—

Figure I is a perspective representation of a single hanger attached to the timbers of a barn and made to support a portion of the track to a hay-carrier. Fig. II is an enlarged elevation of the bracket, nut, and upper portion of the supporting-rod; Fig. III, a plan or top view of Fig. II with nut removed; Fig. IV, an inverted plan view of the central portion of the bracket. Fig. V is a side elevation of the semi-cylindrical nut removed and the supporting-rod.

The purpose of this invention is to provide hangers for the track to a hay-carrier, which may be adjusted to bring the track to any position required, permit the track to have a suitable lateral movement in either direction from a vertical position under the supporting-nut, and to prevent the track from having a longitudinal movement. We accomplish this by a two-winged bracket, which is provided transversely on its central top portion with a semi-cylindrical seat, which has a slot made through it parallel with the wings of the bracket to allow the hanger-rod to pass through. This rod by means of screw-threads is adjustable in an elongated semi-cylindrical nut, which fits the seat in the bracket. The hanger-rod passes through the track and supports it by a head, which can be turned to adjust the track to any height or pitch desired. The wings of the bracket, being curved upward from the base, form strong supports with light metal, and the space between them gives ample room for the upward projection of the screw.

45 N N represent the two wings of the hanger.

bracket, which unite at M in forming a central support for a semi-cylindrical nut, O, the seat R having a contour corresponding to the semi-cylindrical part of the nut O. A slot, K, is formed through the base M of the bracket, 50 parallel with the wings N, whereby the rod P may have a movement in one plane only of about ninety degrees for the purpose of carrying the track S laterally over the hay-compartment for the distribution of hay. The dotted lines 55 V V indicate the deflected position of the track.

It has been the custom in fire-escapes to support the ladder by a semi-spherical washer, so as to give to it a universal movement of about twenty-three degrees of a sphere; but such a 60 device would, if attached to a track, permit it to have a reciprocating longitudinal movement, which would make such track inoperative. Further, the nut which supports the ladder rests on the washer, and could not be 65 used for a track-hanger, for the rod P could not be turned through such nut, because there is nothing to prevent the nut from turning with the rod.

It will be understood that the hangers are 70 placed high up in a barn and are difficult to reach; hence the nut must not turn when the adjustment of the rod is made in it.

We claim as new—

In hangers for tracks for hay-carriers, the 75 bracket consisting of the central base, M, which terminates in the upwardly-projecting supporting-wings N, and has formed transversely in its top portion a semi-cylindrical seat, R, and a slot, K, formed through it parallel with the wings N N, in combination with the semi-cylindrical nut O, the screw-threaded hanger-rod P, adapted to pass through the nut and having a head on its lower end, and the track S, as specified.

WILLIAM H. BURNHAM.
JOHN H. MILLER.
